ELECTRODE FEEDING DEVICE FOR
ELECTRIC ARC APPARATUS

George J. Anderson, Hollywood, Calif., assignor
to Warner Bros. Pictures, Inc., New York, N. Y.,
a corporation of Delaware

Application December 28, 1937, Serial No. 182,053

16 Claims. (Cl. 176—66)

This invention relates to electric arc apparatus and has particular reference to a device for feeding an electrode of an arc lamp.

In arc lamps operated by direct current the major portion of the illumination is derived from a concave crater formed at the tip of the positive electrode or carbon by the arc extending across the tips of the positive and negative electrodes. This crater is therefore positioned at the point where the illumination created thereby can be best utilized, i. e. the focal point of the optical system for the arc lamp.

To insure an unflickering and uniform illumination throughout the cross sectional area of the beam projected by the arc lamp, the crater at the tip of the positive electrode must remain symmetrical and no uneven voltage drop should occur across the tips of the positive and negative electrodes to change the intensity of the light produced thereby.

To permit the whole image of the tip or crater of the positive electrode to be projected by the optical system of the lamp, the negative electrode is generally arranged at an angle to the positive electrode. This requires constant rotation of the positive electrode about its axis to prevent the crater from burning into an unsymmetrical shape and thus projecting an unsymmetrical image. It has been discovered that the best speed of rotation of the positive electrode is dependent upon factors which are different than those factors which determine the longitudinal feed of that electrode to compensate for burning away of the tip thereof.

In cases where a constant voltage is available and where the carbons used all have the same burning rate, the feeding and rotating speeds of the electrodes may be predetermined and the feeding apparatus built accordingly. However, in instances where the voltage supply is not constant, or where carbons of different burning rates are successively employed, it is desirable to regulate the various electrode feeds in accordance with such varying conditions in order to obtain a maximum efficiency of operation. For example, if the voltage of the current supplied to the electrodes is reduced, the electrodes should be fed at a slower speed and vice versa. The motion picture industry is a notable example of a place where such above noted varying conditions exist. In photographing sets or scenes, large numbers of arc lamps are employed, many of which may be turned off and on at different times, thus greatly changing the load conditions of the current supply and consequently effecting a change

in the voltage. The above conditions are especially noticeable in cases where portable generating equipment of relatively small capacity is employed, for example for motion picture production on location or emergency purposes.

One object of this invention is to change the rate of longitudinal feed of an electrode independently of the rate of rotation thereof.

Another object is to change the rate of feed of an electrode while in operation.

Another object is to impart a plurality of feeding impulses to an electrode during each rotation thereof.

Another object is to readily interchange different electrode feeding units in an electric arc apparatus.

Another object is to provide an electrode feeding unit of simple construction and ready accessibility of the parts thereof.

The manner in which the above and other objects of the invention are accomplished will be apparent from the following specification read in conjunction with the accompanying drawings wherein:

Fig. 1 is an elevational view of an electric arc apparatus embodying the present invention.

Fig. 2 is a sectional view partly broken away of the drive shaft assembly for the positive electrode head.

Fig. 3 is a view showing the forward portion of a positive electrode, partly in section.

Fig. 4 is a longitudinal sectional view through the positive electrode head.

Fig. 5 is a transverse sectional view of the positive electrode head and is taken along the line 35 5—5 of Fig. 4.

Fig. 6 is a transverse sectional view of the positive electrode head and is taken along the line 6—6 of Fig. 4.

Fig. 7 is a front view of the spiral gear member.

Fig. 8 is a fragmentary sectional view showing the drive for the electrode carrier and is taken along the line 8—8 of Fig. 4.

Fig. 9 is a transverse sectional view through the electrode gripper gears and is taken along the line 9—9 of Fig. 1.

Referring particularly to Fig. 3 it will be noted that the tip of a positive electrode 10 is formed into a concave crater 11. To effect the maximum efficiency of illumination, it is necessary that the crater 11 be symmetrical and of a definite shape in cross section dependent upon the amount of current and voltage used as well as the type of electrode. The shape and symmetry of the crater 55

are generally governed by the rotation and longitudinal feed of the positive electrode, thus necessitating accurate control of such rotation and longitudinal feed. Usually, both positive and negative electrodes are formed of comminuted 5 carbon bound with a suitable cement.

Referring to Fig. 1, the entire arc apparatus is supported upon a horizontal base 12 which is adapted to be secured at the bottom of a suitable 10 arc lamp housing (not shown) with the crater 11 of electrode 10 situated adjacent the focal point of the optical system of the lamp. A positive head generally indicated at 13 for supporting and feeding the positive electrode 10, and a negative 15 head generally indicated at 14, for supporting and feeding a negative electrode 15, are both supported from base 12 by a standard 16 suitably secured to the upper surface of base 12. Head 13 is electrically insulated from the standard 16 by a layer of insulating material 17. A contacting brush 18 is provided to insure a frictional 20 electrical contact with the positive electrode 10 and is supported from the standard 16 through a bracket 20 suitably insulated from the standard 25 16 by means of insulating material 21. A bus bar 22 electrically connects the brush member 18, through bracket 20, to one end of the coil 30 of an electro-magnet 23 suitably secured to the under surface of the base 12. An insulating bush- 35 ing 22' is provided in base 12 to permit bus bar 22 to pass through the base 12 without contacting the same. A second bus bar 24 connects the opposite end of the coil of electro-magnet 23 to a terminal 25 secured to and insulated from the under surface of base 12.

The negative head 14 is supported on one end of a lever 26 which is pivotally mounted at 27 on the standard 16 to permit movement of the negative electrode 15 toward and away from the 40 positive electrode 10 for the purpose of striking an arc therebetween. Head 14 comprises a base 28 having a downwardly projecting stud member 29 thereon received and adjustably secured within a socket 33 provided at the end of lever 26. 45 A U-shaped bracket 31 is suitably secured on the base 28 and has bearings therein at either end thereof to rotatably support a worm shaft 32 having a pair of oppositely inclined worms 33 and 34 formed thereon. A worm gear 35, meshing 50 with the worm 33, is rotatably mounted on the end of a lever 36 pivotally supported at 37 on the bracket 31. Gear 35 has a cylindrical gripper portion indicated by the dotted lines 38 formed on one side thereof to engage the upper surface 55 of the electrode 15. A second worm gear 40, meshing with the worm 34, is rotatably carried at one end of a second lever 41, pivotally mounted at 42 on the bracket 31. Gear 40 also has a cylindrical gripper portion 43 adapted to engage 60 the under surface of the electrode 15. A compression spring 44 is provided between the opposite ends of the levers 36 and 41 to urge the gripper portions 38 and 43 of the worms 35 and 40, respectively, toward each other and thus secure 65 frictional contact with the electrode 15. A contact brush 45 engaging the forward end of the electrode 15 is hinged at 46 and 47 to the under surface of the base 28 and is urged against the electrode 15 by a spring (not shown) to form an 70 electrical contact. A flexible metallic strap 48 insures an electrical connection between the brush 45 and the lever 26. The standard 16 and base 12, both of metal, form the remainder of an electric circuit between the electrode 15 and 75 a second terminal 50, which is provided on the

under surface of base 12 adjacent the terminal 25. From the above it will be seen that the electrodes 10 and 15 and the electro-magnet 23 are provided in series between the terminals 25 and 50. The lever 26 is urged in a clockwise direction so as to contact the tip of electrode 15 with the tip of electrode 10 for striking purposes by means of a compression spring 51 interposed between the lever 26 and a bracket 52 extending from the standard 16. The rearwardly extending end of the lever 26 is pivotally secured at 53 to a link 54 which, in turn, is pivotally secured at 55 to a second link 56. Link 56 is pivotally supported at 57 by a bracket 58 depending from the under surface of the base 12. An armature 60 provided on the link 56 intermediate the ends thereof is adapted to be drawn into contact with the core 23' of electro-magnet 23 when current is passed through the coil of this electro-magnet to cause the negative head 14 and linkage connected therewith to assume the position illustrated in Fig. 1. In this position the tips of the electrodes 10 and 15 are separated a predetermined amount to support an electric arc therebetween.

A single electric motor 61, suitably secured to the under surface of the base 12, is provided to drive the feeding mechanisms of both the negative head 14 and positive head 13. The connection between the worm shaft 32, forming the driving element of the feeding means on negative head 14, and the motor 61 comprises in series a universal joint 62 coupled to worm shaft 32, an intermediate shaft 63 connected at one end thereof to joint 62 and at the other end thereof to a slip coupling 64, and a second universal joint 65 connecting the coupling 64 to a drive shaft 66 journaled within a bearing 67 formed in the base 12. A ratchet mechanism (not shown) of conventional construction is provided in a suitable housing 68, secured to the under surface of base 12, to transmit an intermittent movement to the intermediate shaft 63. This ratchet mechanism derives its rotation from a gear box generally indicated at 69, the gears (not shown) of which are driven by motor 61.

The mechanism of the positive head 13 which will be described hereinafter is also driven by the motor 61 through gear box 69, a shaft 70, a second gear box 71, the gears of which are not shown, and a drive shaft assembly 72. A rheostat (not shown) may be provided in the motor circuit of motor 61 to vary the speed thereof and thus vary the various feeds of the negative and positive electrodes. However, such a variation in speed will effect a proportionate variation in the feed and rotation of the positive electrode 10 as well as in the feed of the negative electrode 15.

As shown in Fig. 2 the drive shaft assembly 72 is formed into two shaft sections 73 and 74 coupled together by means of a slip coupling 75. The lower end of section 74 is coupled to a gear shaft 76 extending upwardly from the gear box 71 by means of a readily removable coupling 77. Coupling 77 comprises a head 78 secured to shaft 76 and having a longitudinally extending slot 80 formed therein in which extends a transverse pin 81 provided on the lower end of the shaft section 74.

The slip coupling 75 comprises a sleeve 76 secured to the lower end of the shaft section 73 by a pin 82 and has a longitudinally extending slot 83 formed therein in which is guided a transverse pin 84 provided on the upper end of the 75

shaft section 74. A compression spring 85 intermediate the adjacent ends of the shaft sections 73 and 74 urges these sections apart to resiliently retain the lower end of section 74 coupled to the gear shaft 76. The upper shaft section 73 is coupled to the driving mechanism of the positive head 13, to be described hereinafter, by means of a universal joint 86. Joint 86 is electrically insulated from the shaft section 73 by means of an insulated coupling 87.

Referring to Figs. 4 to 8, inclusive, I shall now describe the mechanism of the positive head 13. Head 13 comprises a cylindrical housing 88 having an apertured end wall 89 at the forward end thereof and being open at the rear end thereof. A base 90 is integrally formed on the lower part of housing 88 for the purpose of supporting the head 13 on the standard 16 (Fig. 1). An electrode receiving aperture 91 is provided in the end wall 89, centrally thereof, to permit the positive electrode 10 to be fed therethrough. A cylindrical heat shield 92 of an asbestos or ceramic material having an electrode receiving aperture 92' therein aligned with that of 91 is secured to the end wall 89 of housing 88 by screws 93. Shield 92 acts to prevent the interior of the head 13 from becoming unduly heated by the arc formed across the tips of the positive and negative electrodes. A cylindrical casing 94 open at the end thereof adjacent the open end of housing 88 is fitted over a portion of the outer circumference of housing 88 and is removably secured thereto by screws 95 and 96 (Fig. 6). Housing 88 and casing 94 form a substantially enclosed compartment to house the electrode feeding and rotating mechanism. A bearing counterbore 97 is provided at the rear of the casing 94 and coaxially therewith to receive a ball bearing assembly 98. A cap 99 having a centrally located electrode receiving aperture 100 therein is secured to the end of casing 94 by screws 99' to retain the ball bearing assembly 98 in the counterbore 97 and prevent longitudinal movement thereof. An electrode carrier generally indicated at 101 is rotatably supported by the bearing 98. Carrier 101 comprises a tubular member 102 having a longitudinally extending passage 103 formed therein to loosely receive the electrode 10. Member 102 is mounted in the bore of the inner race 98' of ball bearing 98 and is secured therein by a lock nut 104 screw threaded on the end of member 102. A crown gear member 105 is provided on the member 102 and is held in driving relation therewith by the clamping action of lock nut 104.

Referring to Figs. 4 and 5, it will be noted that the forward portion of the member 102 is formed into an enlarged head 106 having a longitudinal slot 107 extending therethrough. A pair of diametrically opposed, transversely extending, grooves 108 and 109 are formed in the head 106 to receive a pair of stud shafts 110 and 111, respectively. Gripper gears 112 and 113 situated in the slot 107 are rotatably journaled on the shafts 110 and 111, respectively. Tension springs 114 and 115 are provided between the ends of the shafts 110 and 111 to resiliently urge the teeth of the gears 112 and 113 into engagement with the positive electrode 10. A spiral gear member 116 is rotatably journaled upon a bearing portion 117 formed on the member 102 directly behind the head 106. Gear 116 has a set of spiral gear teeth 121 on one face thereof, which teeth mesh with the teeth of the gripper gears 112 and 113, and are adapted to rotate the gears

112 and 113 about their respective axes on relative rotation of the tubular member 102 and the gear 116. A plurality of serrations or detents 122 are spaced around the periphery of gear 120.

A three lobed cam 123 is secured by screws 124 to the face of crown gear 105 adjacent the gear 116. A cam follower 126, movably supported by the casing 94, has a ball bearing 127 mounted in the lower end thereof which bearing is adapted to ride on the surface of cam 123 to intermittently raise the cam follower in a vertical direction. Follower 126 is slideable vertically in a guide 128 secured to the upper surface of casing 94 by screws 129. A compression spring 130 provided in a well 131 formed in the guide 128 urges the cam follower 126 downward at all times. A stop screw 132 is screw threaded vertically within the follower 126 and has a conical point 133 therein adapted to engage any one of the serrations 122 of gear member 116 when the ball 127 of the cam follower 126 rides upon a flattened portion 134 of the cam 123. Screw 132 extends to the exterior of the head 13 and has a knob 135 thereon whereby it may be adjusted vertically by an operator from the exterior of the head 13 and while the apparatus is in operation. A lock nut 136 is provided to lock the screw 132 in any desired position.

Crown gear 105 is meshed with a pinion 137 carried on a stub shaft 138. Shaft 138 is journaled within a bearing bushing 139 carried by a boss 140 which is secured to the under surface of the casing 94 by screws 141. The shaft 138 of pinion 137 is suitably secured to the universal joint 86 (Fig. 1).

In operation, the positive electrode 10 is inserted through the aperture 100 in cap 99 of head 13, thence through the bore 103 of member 102, and thence between the gripper gears 112 and 113. Since gears 112 and 113 are resiliently urged toward each other by the tension springs 114 and 115 these gears will be merely spread apart by insertion of the electrode 10 therebetween and will frictionally engage diametrically opposed portions thereof. Thereafter the electrode 10 is moved past the brush 18 and in frictional contact therewith.

The negative electrode 15 is inserted in the rear of the negative head 14. By pressing the levers 36 and 41 together at a point adjacent the spring 44 the gripper portions 38 and 43 of the worm gears 35 and 40, respectively, will be moved outwardly permitting the electrode 15 to be passed therebetween. The electrode 15 is thence moved past the contact brush 45 in frictional contact therewith.

The tips of the electrodes 10 and 15 are adjusted in correct relation with each other, these tips being in contact with each other before current is passed thereacross. When current is applied across the terminals 25 and 53 the closed circuit caused by the tips of electrodes 10 and 15 contacting each other will permit the electro-magnet 23 to be actuated to effect a counter-clockwise movement of the lever 26 against the action of the spring 51, this movement being limited by the engagement of the armature 60 on link 56 with the core 23' of the electro-magnet 23. Due to the path of the volatilized carbon particles extending between the now separated tips of electrodes 10 and 15, the current will continue to pass thereacross forming an arc.

On operation of the electric motor 61, which is preferably started simultaneously with the 75

striking of an arc between the electrodes 10 and 15, the worm shaft 32 will be intermittently rotated to feed the electrode 15, through the worm gears 35 and 40 and their respective gripper portions 38 and 43. Rotation of motor 61 will also cause the crown gear 105 in positive head 13 to rotate continuously, thus effecting rotation of the positive electrode 10 by virtue of the frictional engagement therewith of the bodily moved gripper gears 112 and 113 carried by the tubular member 102. When the cam follower 126 engages a lobe of cam 123 the stop screw 132 will be raised out of engagement with one of the serrations 122 formed on the gear member 116. Thus gear member 116 will be permitted to rotate with the member 102 resulting in a cessation of the longitudinal feed of the electrode 10. However, as one of the flattened portions 134 of cam 123 rides under cam follower 126 the stop screw 132 will be lowered into engagement with one of the serrations 122 of gear 116 thus holding this gear in fixed relation with the casing 94. As the tubular member 102 continues to rotate while the gear 116 is locked against rotation by the screw 132 the relative movement between spiral gear 116 and the member 102 will cause the gripper gears 112 and 113 to be rotated about their respective axes while being rotated as a whole about the axis of the electrode 10 to impart a longitudinal feeding movement to this electrode. This feeding movement will continue until the cam follower 126 is again raised by a successive lobe on cam 123. By adjustably raising or lowering screw 132 the interval of time during which the conical point 133 of screw 132 is engaged with one of the serrations 122 on gear member 116 may be regulated, thus regulating the amount of each feeding impulse. That is, if the stop screw 132 is adjustably lowered relative to the cam follower 126 the conical point 133 thereof will engage one of the serrations 122 at an earlier moment on the downward travel of cam follower 126 and will be disengaged from that serration at a later moment, thus holding the gear member 116 in a fixed position for a longer period of time and effecting a greater longitudinal feed of electrode 10 while a flattened portion 134 of cam 123 passes under the cam follower 126. It will be noted that adjustment of screw 132 effects regulation of the longitudinal feeding movement of the electrode 10 independently of the rate of rotation thereof about its axis. Since each feeding impulse is of considerable duration and since there are a plurality of impulses for each revolution of the electrode 10, it will be noted that the slight unevenness of longitudinal feeding movement imparted to the electrode 10 will be insufficient to cause a flicker or change in illumination of the arc.

Screw 132 may be adjustably lowered to such a point in the cam follower 126 that the conical point 133 thereof will remain in engagement with a serration of the gear 116 during an entire rotation of the cam 123. In this event a continuous longitudinal feed may be imparted to the electrode 10.

In lieu of the three lobed cam 124 imparting three longitudinal feeding impulses to the electrode 10 for each rotation of the electrode carrier 101, a cam having any number of lobes may be substituted therefor to give any number of longitudinal feeding impulses for each revolution of carrier 101. Furthermore gears similar to that of 116 but having serrations of a different pitch

may be substituted to permit a finer or coarser control of the length of each longitudinal feeding impulse.

In the event that the positive head 13 is to be repaired or cleaned or that a similar unit is substituted therefor, the casing 94 carrying thereon the rotatable electrode holder 101 may be readily detached from the housing 88 by removal of the two screws 95 and 96 (Fig. 6). The casing 94 may then be slipped out of engagement with the housing 88 and the lower end of the drive shaft 72 carrying the transversely extending pin 81 (Fig. 2) may be slipped out of the coupling member 78. This feature is especially valuable in arc lamps used in the motion picture industry where delays caused by replacement of feeding units in arc lamps are considerably expensive.

Although the invention has been described as being embodied in a feeding unit for a positive electrode, and although it is particularly applicable thereto, it is to be understood that the invention may also be applied to the feeding unit of a negative electrode as well.

I claim:

1. An electrode feeding device for electric arc apparatus comprising an electrode carrier, means for rotatably supporting said carrier, means comprising a gear on said carrier for longitudinally feeding an electrode, a cam on said carrier, a cam follower for said cam, means for movably supporting said cam follower, a screw holder actuated by said cam follower, and a screw adjustably mounted in said screw holder for intermittently engaging said gear to control the operation of said feeding means.

2. An electrode feeding device for electric arc apparatus comprising a casing having a wall, an electrode carrier rotatably supported by said casing, means for rotating said carrier, said carrier having an electrode receiving passage therein in coaxial with the axis of rotation thereof, a member supported by said carrier for relative independent rotation about an axis co-axial with the axis of rotation of said carrier, said member being normally rotatable with said carrier, means operatively connected to said member and said carrier and on relative rotation of said carrier and said member imparting a feeding movement to an electrode in said passage, a cam operatively connected to said carrier, a reciprocating cam follower engaging the working surface of said cam, means on said casing for supporting said cam follower, a stop member extending through said wall and carried by said cam follower and adapted to engage the periphery of said first mentioned member to interrupt rotation thereof, said stop member being adjustable from the exterior of said casing and in the direction of reciprocation of said cam follower to vary the length of time said stop member is in engagement with said first mentioned member.

3. An electrode feeding device for electric arc apparatus comprising a housing, a casing removably attached to said housing, said housing and casing forming an enclosure, an electrode carrier rotatably supported by said casing and extending into said enclosure, said housing, casing, and carrier having co-extensive apertures therein to receive an electrode, a cam on said carrier, means on said carrier for feeding an electrode through said apertures, and means movably supported by said casing and adapted to be actuated by said cam for controlling said first mentioned means.

4. An electrode feeding device for electric arc apparatus comprising a housing having an electrode aperture, a casing attached to said housing and having an aligned electrode aperture, means for attaching said casing to said housing, an electrode carrier, means for rotatably supporting said carrier in said casing, means on said carrier for feeding an electrode longitudinally, means carried by said casing for rotating said carrier, a drive shaft for said last mentioned means and a removable coupling for said drive shaft. 5
5. An electrode feeding device for electric arc apparatus comprising a housing having an electrode aperture, means for supporting said housing in a fixed position, a casing, means for removably attaching said casing to said housing to form a compartment, said casing having an electrode aperture therein aligned with said first mentioned aperture, electrode feeding means for feeding an electrode through said apertures, means in said casing for supporting said feeding means in said compartment, a gear in said casing operatively connected to said feeding means, a second gear rotatably supported by said casing and meshing with said first mentioned gear, driving means for said second gear, and a removable coupling intermediate said driving means and said second gear, whereby said casing and said electrode feeding means may be readily detached from said housing and said driving means. 10
6. An electrode feeding device for arc apparatus comprising a cylindrical housing having an open and a substantially closed end, a cylindrical casing having an open and a substantially closed end, the open end of said casing fitting the open end of said housing to form a compartment, means for removably securing said casing to said housing, the closed ends of said housing and casing having aligned electrode apertures therein, an electrode carrier rotatably supported in the aperture of said casing and extending into said compartment, said carrier having a passage therein aligned with said apertures to receive an electrode therein, means carried by said casing for rotating said carrier, means carried by said carrier and said casing adapted to feed said electrode through said apertures and passage on rotation of said carrier, a drive shaft for said first mentioned means and a removable coupling for said drive shaft. 15
7. An electrode feeding device for arc apparatus comprising a cylindrical housing, means for supporting said housing, said housing having an apertured wall at one end and being open at the other end, a casing having an apertured wall at one end and being open at the other end, means for removably securing the open end of said casing to the open end of said housing to form a compartment, said casing having a bearing bore in the apertured wall thereof, an electrode carrier, bearing means in said bore for rotatably supporting a carrier in said compartment, said carrier and the apertured end wall of said housing having aligned passages therein to receive an electrode, means on said carrier and actuated by said carrier for feeding an electrode through said passages, a gear on said carrier, a second gear meshing with said first mentioned gear, means in said casing for supporting said second gear for rotation about an axis normal to the axis of said first mentioned gear, means for driving said second gear, and a removable coupling intermediate said second gear and said driving means. 20
8. In an electrode feeding device for electric arc apparatus, the combination comprising a casing, a driving member rotatably supported in said casing, a cam connected to said driving member, a driven member mounted in said casing for rotation about an axis co-axial with the axis of rotation of said driving member, means normally forming a driving connection between said driving and driven members, feeding means operatively connected to said driven member for feeding an electrode, a cam follower in engagement with the working surface of said cam, a guide member having a sliding bearing surface for supporting said cam follower for reciprocation, and a stop screw threaded in said cam follower and adapted to engage said driven member to interrupt the rotation thereof when said cam follower is reciprocated. 25
9. Electrode feeding mechanism comprising the combination of a casing having a bearing at one end thereof, an electrode tube in said bearing, a feed gear and a cam mounted side by side in said casing on said tube at the same side of said bearing, a guide member on said casing opposite said gear and said cam, a follower for said cam in said guide member, and means on said follower for stopping said gear in certain positions of said cam. 30
10. Electrode feeding means according to claim 9 wherein said stopping means comprises an adjustable member, and a hand operating device therefor accessible at the exterior of said casing. 35
11. In an electrode feeding device for electric arc apparatus, the combination of a casing, means for feeding an electrode comprising a carrier and gripper wheels mounted thereon, a feed gear on said carrier for operating said gripper wheels, a bearing for rotatably supporting said carrier in said casing at one side of said bearing, a cam in said casing adjacent said feed gear and at the same side of said bearing as said feed gear, means for rotating said cam about an axis coaxial with the axis of rotation of said feed gear, means comprising said carrier normally forming a driving engagement between said feed gear and said cam; a cam follower engageable with the working surface of said cam, and a stop member operated by said cam follower and adapted to engage said feed gear to interrupt the rotation of said feed gear at certain times. 40
12. Electrode feeding mechanism for arc apparatus comprising the combination of casing having a closed end, an open end, and a circumferential side wall, a housing having a closed end and an open end, aligned electrode apertures in the closed ends of said casing and housing, the open ends of said casing and housing being fitted together to form a compartment, a bearing in the closed end of said casing, an electrode tube rotatably mounted in said bearing and extending into the open end of said casing, a drive gear having a cam thereon mounted on said extended end of said electrode tube, a scroll gear having a serrated circumference mounted on the extended end of said electrode tube closely adjacent to said cam, an aperture in the side wall of said casing, a guide member mounted in said aperture, a cam follower for said cam mounted in said guide member, and a stop screw carried by said cam follower and having an inner end cooperating with the serrations of said scroll gear and having an outer end accessible from the exterior of said casing for adjusting the electrode feed. 45
13. An electrode feeding device for electric arc apparatus comprising an electrode carrier, means 50
- 75

for rotatably supporting said carrier, means comprising a spiral gear, having serrations thereon, on said carrier for longitudinally feeding an electrode, a cam on said carrier, said cam having a 5 lobe with an extended working surface, a cam follower for said cam, means for movably supporting said cam follower, a screw holder actuated by said cam follower and a screw adjustably mounted in said screw holder for intermittently 10 engaging said serrations to control the operation of said feeding means.

14. An electrode feeding device comprising the combination of an electrode carrier, a casing over 15 said carrier having a substantially closed end, a bearing in said closed end for rotatably supporting said carrier, feed means on said carrier, and within said casing for feeding an electrode through said carrier, a cam fixed on said carrier

intermediate said feeding means and said bearing, means operable by said cam for controlling said feeding means, and a driven member on said carrier intermediate said cam and said bearing for rotating said carrier. 5

15. An electrode feeding device according to claim 14, comprising means on said casing for supporting said cam operable controlling means.

16. An electrode feeding device according to claim 14, comprising driving means supported by 10 said casing for driving said driven member, said casing comprising a pair of sections, means removably securing said sections together, one of 15 said sections supporting said bearing and said driving means, and means for supporting the other of said sections.

GEORGE J. ANDERSON.
